(57) **CLAIM**

The ornamental design for a headset with charging case as shown and described.

DESCRIPTION

FIG. 1 is an exploded front, right and top perspective view of a headset with charging case, showing our new design. FIG. 2 is an exploded rear, left and bottom perspective view thereof.

FIG. 3 is an exploded front elevation view thereof.

FIG. 4 is an exploded rear elevation view thereof.

FIG. 5 is an exploded left side elevation view thereof.

FIG. 6 is an exploded right side elevation view thereof.

FIG. 7 is an exploded top plan view thereof.

FIG. 8 is an exploded bottom plan view thereof.

FIG. 9 is another perspective view of the headset with charging case in a first usable state; and,

FIG. 10 is another perspective view of the headset with charging case in a second usable state.

The dashed broken lines depict portions of the headset with charging case that form no part of the claimed design.

1 Claim, 10 Drawing Sheets
